THOMAS EDISON, OF WINDSOR, ONTARIO, CANADA, ASSIGNOR TO THE DETROIT VAPOR STOVE COMPANY, OF DETROIT, MICHIGAN, A CORPORATION OF MICHIGAN.

HYDROCARBON-BURNER.

1,188,742.

Specification of Letters Patent. Patented June 27, 1916.

Application filed November 19, 1915. Serial No. 62,296.

To all whom it may concern:

Be it known that I, THOMAS EDISON, a subject of the King of Great Britain, residing at Windsor, county of Essex, Province of Ontario, Canada, have invented a certain new and useful Improvement in Hydrocarbon-Burners, and declare the following to be a full, clear, and exact description of the same, such as will enable others skilled in the art to which it pertains to make and use the same, reference being had to the accompanying drawings, which form a part of this specification.

This invention relates to hydrocarbon burners and comprises a ring-like cap which removably sets upon the top of the burner to both centralize the heat and flame and aid the action of the burner by keeping away objectionable air currents.

20 In the drawings, Figure 1, is a side view of the burner partly in section showing a cross section of the ring-like cap. Fig. 2, is a bottom view of the cap showing the inside construction.

25 The burner here shown is one calculated to burn hydrocarbon, such as kerosene or gasolene. It comprises four annular shells provided with horizontal slots through which the air enters the two annular chambers *a* and *b* and mixes with the vaporizing hydrocarbon to form a combustible mixture. The hydrocarbon is carried in the troughs *d* and *e* and is vaporized by the heat communicated to these troughs from 30 the burner. This much of the construction is old.

The outer annular slotted shell *f* is provided with an outwardly-extending flange *g* which turns first outward and then downward. A thin metal band *h* extends from this flange to the bottom of the burner and is held in spaced relation from the outer slotted annular shell *f* by means of the spacers or wings *i* which extend outwardly from the outside annular slotted shell *f*, they being part of the casting which forms this shell.

These wings or spacers serve to keep the sheet metal band *h* properly spaced and this forms a guard for the burner to prevent sudden entry of the air into the mixing chambers.

My invention comprises the mounting of a cap in the form of a ring arched in cross-section over the outside edge of the burner. 55 This ring is designated *j* and comprises a casting which forms the ring, shaped on an arc in cross-section, and provided with integral feet *k* which are cut away at the bottom to fit over the flange *g* of the outer 60 annular shell *f*. It will be noted that these feet *k* are of the proper length and dimensions to hold the bottom of the cap in spaced relation with the main body of the burner. 65 This gives an air space annular in its entirety, which allows the entry of the air to the top of the burner to support combustion.

It will be noted that the top of the cap *j* extends partially, (except for the recess for lighting the fuel mixture in the outer 70 chamber *b*) and almost entirely, over the upper end of the mixing chamber *b* whose upper end may be said to be the zone of combustion. This cap, therefore, tends to deflect the flame and heat issuing from the 75 outer end of the chamber *b* toward the inner annular chamber *a*, and thereby concentrates the heat and flame toward the center of the burner where it can be more efficiently utilized in cooking and none of the heat is dissipated at the side of the vessel used in cooking. This cap also acts as a protecting hood to keep away objectionable drafts which would tend to blow out or disturb the flame from the burner. Hydrocarbon burners of this character are very susceptible to drafts, and inasmuch as the mixture, especially heavy hydrocarbon, prepared for combustion is not as inflammable as the ordinary coal gas, it is necessary that the burner 80 be protected as much as possible to avoid these objectionable drafts. 85

Inasmuch as the feet *k* merely set upon the flange *g*, the cap may be removed whenever desired, as when a more diffused flame 95 is wanted, to make repairs, or for cleaning.

It will, of course, be understood that this burner sets under a grid (not shown) which holds the cooking utensils in the customary way.

What I claim is:

In a hydrocarbon burner, the combination of a plurality of annular shells provided with openings through the sides and

forming one or more mixing chambers and the outer shell of which is provided with a flange, means for supplying vaporized oil to the same, and a ring-like cap, said cap being provided with feet on its inside whose lower portions are cut away to fit over the top of the outer annular shell and the said

flange to removably hold the cap in place and spaced at its bottom from the body of the burner to form an annular air space, 10 substantially as described.

In testimony whereof I sign this specification.

THOMAS EDISON.
